UNITED STATES PATENT OFFICE.

ERLE STAFFORD HUNTLEY, OF FRIEZLAND, QUEENSLAND, AUSTRALIA, ASSIGNOR TO
THE HAMPDEN CLONCURRY COPPER MINES LIMITED, OF MELBOURNE, AUSTRALIA.

GAS-PRODUCER.

1,300,839.

Specification of Letters Patent. Patented Apr. 15, 1919.

Application filed February 23, 1916. Serial No. 79,911.

To all whom it may concern:

Be it known that I, ERLE STAFFORD HUNTLEY, general manager of the Hampden Cloncurry Copper Mines Limited, of Friezland, in the State of Queensland, Commonwealth of Australia, subject of the King of Great Britain, residing at Friezland, in the State of Queensland, Commonwealth of Australia, have invented certain new and useful Improvements in Gas-Producers, of which the following is a specification.

This invention relates to an improved gas producer for the generation of gaseous fuel and refers more particularly to a producer for the generation of gas for power purposes from wood, charcoal, coke, coal or other like suitable fuel.

The object of this invention is to provide a producer in which gas is generated for use in the production of power in a cheaper and more efficient manner than heretofore.

This invention comprises a vertical chamber having a feed at the top for the introduction of the primary fuel, a series of twyers for the introduction of free air underneath the primary fuel, an exit for the gas beneath the said twyers, a grate at the bottom and means for the introduction of air and steam beneath the said grate. By this arrangement an incandescent zone is provided underneath the primary fuel and above the gas exit and another incandescent zone above the grate and beneath the gas exit and the gas is withdrawn from the producer at about the center of the body of fuel so that there are two distinct incandescent zones, one above the gas outlet and the other below the same. Provision is made for the introduction of steam into the feed chamber with the primary fuel which prevents the incandescent zone opposite the aforesaid twyers from rising.

This invention will now be more fully described aided by a reference to the accompanying sheet of drawings in which—

Figure 1 is a longitudinal sectional elevation of a producer taken on line 2—2 of Fig. 2 while

Fig. 2 is a plan of the same.

Fig. 3 is a cross sectional elevation taken on line 3—3 of Fig. 2.

A gas producer constructed according to this invention comprises a vertical chamber A constructed preferably of sheet metal lined with firebrick or other fire resisting

material A'. This vertical chamber A is furnished with a semicircular or arched dome or cover B at its top having suitable feed door or doors B' for the supply of fuel. The main body of the producer is constricted at or about the center A² whereby two distinct chambers are afforded the upper A³ being adapted for the combustion of the primary fuel, and the lower A⁴ for the combustion of the fixed carbon and secondary fuel after having passed through the upper chamber. At the bottom of the upper rectangular chamber A³ are provided means for the introduction of air underneath the primary fuel which comprise a series of twyers C arranged in the walls of the said chamber immediately above the constriction A² while a series of air inlets or twyers C' are also arranged around the said constriction. These inlets or twyers may be furnished with controlling valves adapted to regulate the supply of air therethrough. In the bottom of the lower cylindrical chamber A⁴ is fitted a fire grate D beneath which are arranged openings E for the admission of air under the incandescent fuel and these openings E may be furnished with valves for controlling the admission of air. These openings E are also adapted for removing the ashes (if any) from beneath the grate D. Above the grate D are arranged poking holes D'. Just below the constriction A² that is to say between the two zones of combustion is provided an outlet F for the gaseous fuel. Within the said chamber A⁴ and opposite to the said outlet F is an inverted U-shaped bridge F' constructed of firebrick or fire clay or cast iron (water jacketed if necessary). The said gas outlet F communicates with a chamber G within which heating pipes are provided for the vaporization of water and from which the gas passes to the necessary scrubbers, coolers and cleaners and thence to the gasometers or otherwise as may be desired. Steam pipes J leading from the vaporizer G or other source of steam are provided for supplying steam to the feed chamber B and through one or more of the air openings E beneath the grate D in such quantities as may be required.

In operation the wood or other fuel is fed into the feed chamber B through the rectangular chamber A³ at its top and descends in the column of this vertical chamber until it comes into the upper zone of combustion

where the admission of air through the twyters C C' causes it to be partly converted into producer gas and partly into charcoal or fixed carbon. This charcoal or fixed carbon descends past the gas outlet F into the lower zone of combustion in the cylindrical lower chamber A⁴ above the grate D where it is finally consumed. The gas is drawn off from both the upper and lower zones of combustion simultaneously at about the center through the gas outlet F by suction and passes thence to the scrubbers, cleaners, and coolers for use as required.

I claim—

15. A gas producer, comprising in combination, a vertical chamber having a constriction dividing the same into upper and lower compartments, a cover for said chamber pro-

vided with feed openings, a series of twyters introducing air into the upper compartment, 20 a second series of twyters introducing air at said constriction, a gas outlet, an inverted U-shaped bridge within the lower chamber opposite to and communicating with said outlet, a grate at the lower part of said 25 lower chamber, means for admitting air beneath said grate, a vaporizer, and a steam pipe leading from said vaporizer and supplying steam into said chamber at the top and bottom thereof.

In testimony whereof I have affixed my signature in presence of two witnesses.

ERLE STAFFORD HUNLEY.
